Primary Examiner — John Windmuller*Assistant Examiner* — John R Yeh(74) *Attorney, Agent, or Firm* — Irina Hass(57) **CLAIM**

The ornamental design for a cleaning article, as shown and described.

DESCRIPTION

FIG. 1 is a perspective view showing the new design for a cleaning article;

FIG. 2 is a top view thereof;

FIG. 3 is a right side view thereof;

FIG. 4 is a left side view thereof;

FIG. 5 is a front view thereof;

FIG. 6 is a rear view thereof; and,

FIG. 7 is a bottom view thereof.

The portions of the cleaning article in FIGS. 1, 3-7 shown in broken lines are included to show features that form no part of the claimed design.

1 Claim, 3 Drawing Sheets(56)
